ADJUSTABLE WRENCH

Sherman Hare, Grantsville, Md., assignor of one-half to Emery Georg, Accident, Md.

Application July 22, 1937, Serial No. 155,106

2 Claims. (Cl. 81—163)

This invention relates to wrenches, and more particularly to wrenches of the adjustable jaw type.

An object of this invention is to provide a wrench of this character wherein the jaws thereof will be firmly held in adjusted position and will not readily get out of adjustment until the adjusting means has been moved.

Another object of this invention is to provide a wrench which combines adjustable jaws and a ratchet mechanism so that the head of the wrench may be progressively rotated relative to the handle.

A further object of this invention is to provide in a wrench of this character a novel adjusting mechanism for the jaws which is carried by the head of the wrench.

Still another object of this wrench structure is to provide means whereby sockets or like nut engaging devices may be clamped between the jaws, or dies or other thread cutting devices may be secured between the jaws, the ratchet mechanism permitting the progressive turning in a selected direction of the head with respect to the handle.

Further objects and advantages of my invention are more apparent from the accompanying drawing and description, wherein like characters of reference are used to designate similar parts throughout the specification.

In the drawing, Figure 1 is a top plan, partly broken away and in section of a wrench constructed according to an embodiment of this invention, the operating member for adjusting the jaws being removed from the head of the wrench.

Figure 2 is a sectional view taken on the line 2—2 of Fig. 1.

Figure 3 is a sectional view taken on the line 3—3 of Fig. 1.

Figure 4 is a sectional view taken on the line 4—4 of Fig. 1.

Figure 5 is a fragmentary bottom plan, partly in section of the wrench.

Figure 6 is a fragmentary bottom plan showing a modified form of jaw structure used with this invention.

Referring to the drawing, the numeral 10 designates generally a handle having an annulus 11 at its outer end and in which a head 12 engages. The head 12 comprises a pair of substantially half-round parts 13 and 14 which may be suitably secured to a pair of plates 15 and 16, the plates 15 and 16 holding the members 13 and 14 together.

A pair of jaw members 17 and 18 are disposed within the head 12, having a portion thereof pro-

jecting exteriorly of the head 12 and a portion thereof projecting interiorly of the head 12. The portions 19 and 20, respectively of the jaws 17 and 18 projecting interiorly of the head 12 engage in oppositely extending channels 21 and 22, respectively, and enlarged blocks or lugs 23 and 24, respectively are integral with the slide portions 19 and 20, respectively.

Preferably the plates 15 and 16 are each provided with a groove 25 in which a bead 26 at each end of a jaw engages so that the jaw members will be held against turning movement in the head 12. The jaws 17 and 18 are moved relative to each other by rotation of a pair of threaded shafts 27 which are each provided with right and left hand threads so that rotation of the shafts 27 in one direction will move the jaws 17 and 18 away from each other, and rotation of the shafts 27 in the opposite direction will draw the jaws 17 and 18 together or toward each other. The inner end portions 23 and 24 of the jaws 17 and 18 are provided with a pair of threaded openings to receive the shafts 27, and the jaws 17 and 18 are adapted to move in parallelism.

Each shaft 27 is provided in substantially the center thereof with a worm gear 28 which is adapted to mesh with a worm 29 rotatably carried by the head 12. A pinion or spur gear 30 is secured to each worm 29, and the gears 30 mesh with an internal gear 31 carried by a cap 32. The cap 32 is rotatably held on the head 12 by means of pins 33 which engage in an annular groove 34 provided in the head 12. The cap 32 is provided with a central opening 35 so that a finger or the like may be projected thereinto for engagement with a locking pawl 36. The pawl 36 is spring-pressed and the bill thereof is adapted to engage the internal gear 31 to hold this gear 31 against rotation in a direction to permit movement of the jaws 17 and 18 away from each other. When the worms 29 are stationary the worm gears 28 will be locked against rotation, but the pawl 36 is provided to insure positive locking of the jaws 17 and 18 against opening after they have been set.

The periphery of the head 12 is provided with a plurality of circumferentially spaced apart notches 37 in which ratchet pawls 38 and 39 are adapted to engage, the pawls 38 and 39 being rockably mounted on pins 40 and 41, respectively, 50 engaging in the outer end of the handle 10. The pawls 38 and 39 are urged to an operative position by means of a spring 42, there being a spring 42 for each pawl 38 and 39.

A pair of slide members 43 and 44 are slidably

carried by the handle 10 inwardly of the inner ends of the pawls 38 and 39, the slide members 43 and 44 being provided with T-shaped slide portions 45 and 46, respectively, which slidely engage in T-shaped channels provided in the handle 10. The pawls 38 and 39 are provided with beveled inner ends 47 and 48, respectively, which are initially engaged by the outer ends of the slide members 43 and 44, respectively, and 5 the beveled portions 47 and 48 terminate in shoulders 49 and 50, respectively, against which the outer ends of the slide members 43 and 44 are adapted to engage so as to hold the pawls 38 and 39 in inoperative position. Movement of the 10 slide member 43 outwardly to engage the shoulder 49 of the pawl 38 will permit free rotation of the handle 10 in a counter-clockwise direction with respect to the head 12, and movement of the slide 44 forwardly to engage the shoulder 40 15 will permit free rotation of the head 12 in a clockwise direction.

In Figure 4 the jaw members 17 and 18 are shown as having flat confronting faces, whereas in Fig. 6 the jaw members 17' and 18' are provided with a V-shaped jaw portion in substantially the center thereof, as shown at 51 and 52, respectively.

In the use and operation of this wrench, the jaws 17 and 18 are set relative to each other by 20 releasing the pawl 36 and then turning the toothed cap 32 which comprises the jaw operating member. Turning the cap 32 in one direction will effect turning of the spur gears or pinions 30 and rotation of the worms 29. Rotation 25 of the worms 29 will likewise rotate the worm gears 28, and when the worm gears 28 rotate in one direction the threaded shafts 27 will effect movement of the jaws 17 and 18 away from each other. The jaws 17 and 18 are adapted to directly contact with the faces of the nut or bolt, but if desired a socket may be clamped between the jaws 17 and 18 and the socket then engaged with the nut or bolt.

It will be apparent from the foregoing that an 30 exceedingly practical wrench structure has been

provided which may be used for tightening or loosening nuts and bolts of sizes coming within the capacity of the jaws 17 and 18, and if desired dies or the like may also be clamped between these jaws for the purpose of forming threads. 5

It is, of course, understood that various changes and modifications may be made in the details of this invention, such changes and modifications being limited only by the scope of the appended claims. 10

What is claimed is:

1. A wrench comprising a handle, an annulus, carried by said handle, a head rotatably engaging in said annulus, a pair of jaw members, means slidably securing said jaw members on said head, 15 a pair of oppositely threaded shafts carried by said head and engaging said jaw members to move said jaw members relative to each other, a worm gear fixed on each shaft, a worm for each worm gear rotatably carried by said head, a spur gear fixedly secured to each worm, an internally toothed cap carried by said head and engaging said spur gears, ratchet means for said head, and means locking said cap against rotation relative to said head. 25

2. A wrench comprising a handle, an annulus carried by said handle, a head rotatably engaging in said annulus, a pair of jaw members, means slidably securing said jaw members on said head, 30 a pair of oppositely threaded shafts carried by said head and engaging said jaw members to move said jaw members relative to each other, a worm gear fixed on each shaft, a worm for each worm gear rotatably carried by said head, a spur gear fixedly secured to each worm, an internally toothed cap carried by said head and engaging said spur gears, opposed ratchet members carried by said handle, said head having notches in the periphery thereof to receive said ratchet members, a locking member for each ratchet 35 member slidably carried by said handle, and means carried by said head engageable with the teeth of said cap to lock said cap against rotation relative to said head. 40
